UNITED STATES PATENT OFFICE.

ARTHUR F. BENNETT, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE APPARATUS.

Application filed August 20, 1925. Serial No. 51,301.

This invention relates to acoustic devices and particularly to telephone transmitters.

An object of the invention is to improve the operation of telephone transmitters and 5 to effect economies in their manufacture.

In accordance with one feature of the invention a telephone transmitter is provided with a light, substantially aperiodic diaphragm having its central portion, which 10 forms a closure for the chamber containing the granular carbon, slightly dished to control resistance changes due to the thermal action of the carbon button.

Another feature provides for frictionally 15 securing the elements of so-called book damping means together to make handling of the separate elements unnecessary.

In the specific embodiment hereinafter 20 described as applied to a transmitter, the diaphragm is conical in shape with a center portion practically flat but sufficiently conical or dished to compensate for the thermal action of the carbon button, with respect to which it forms a closure and acts as an agitator for the carbon material. The periphery is provided with a channel and the conical surface of the diaphragm is provided 25 with radial corrugations. The diaphragm is mounted between book damping members 30 disposed on each side at its periphery to control its vibrations and permit free radial expansion and contraction. Between the carbon and the central portion of the diaphragm is disposed another book damping 35 element which serves to some extent to control the action of the diaphragm and at the same time to prevent the leakage of the carbon granules from the chamber.

The book damping members consist of 40 rings of paper or foil stacked and, in accordance with the invention, these rings are pierced with a suitable tool, such as a needle, to form telescoping projections or burrs, the burrs on adjacent sheets frictionally engaging 45 into a secure frictional hold.

Referring to the drawings:—

Fig. 1 is a cross sectional view of a microphone transmitter embodying the invention;

50 Fig. 2 is a front view of the diaphragm;

Fig. 3 is a plan view of one of the mounting and damping members, and

Fig. 4 is a cross sectional view through the mounting and damping members on line 55 4—4 of Fig. 3.

A cup-shaped member 5 is provided with a central aperture formed by an internally extended cylindrical portion 6, and an off-set threaded rim having a ledge 7. The inner edge of the portion 6 is provided with an inwardly projecting flange 8 and an annular recess 9. The flange 8 forms one electrode of a barrier type transmitter button such as is disclosed in U. S. Patent 1,565,581 granted to C. R. Moore on Dec. 15, 1925. An annular member 10 forms the other electrode of the carbon button and is insulated from the cylindrical portion 6 by insulating members 11, 12, and 13. The chamber formed by the electrodes 8 and 10 is closed at one end by a disc 15 provided with a terminal 16. The inner surface of the disc 15 is preferably covered with a suitable insulating material 17 to insulate it from the carbon granules. The electrode 10 and its insulating members are secured in place by a nut 19 having threaded engagement with the cup member 5. The other side of the carbon chamber is closed by a diaphragm 20 and a plurality of thin annular members 21 made of paper or foil and loosely disposed in the recess 9 between the diaphragm 20 and the electrode 8. These rings, in addition to preventing the granular carbon from escaping, provide damping for controlling the vibrations of the diaphragm. Since they are not packed tightly, air films are permitted to form between adjacent rings which serve to dissipate the energy according to well known theories of air damping. The diaphragm 20 is loosely supported on the ledge 7 between stacks of thin rings 22 and 23 by means of washer 24 and nut 25 which has threaded engagement with the case 5. These rings act as air damping means as described and claimed in U. S. Patent 1,660,990, granted to H. F. Dodge on Feb. 28, 1928. Between the book damping member 22 and the washer 24 is a moisture-proof diaphragm 40:

The unit described herein may be supported in the usual transmitter casing comprising a face plate 26 and a bell 27. Preferably, the unit is insulated from the face plate by an insulating washer 28 and secured thereto by means of an annular member 29 of insulating material and screws 30. Between the face plate 26 and the nut 28 is a wire gauze protecting member 41.

The diaphragm 20 is conical in form and made of aluminum alloy, magnesium

or any light material. Duralumin having a thickness of .002" to .003" has been found very satisfactory for the purposes of the invention. It is stiffened by radial corrugations to prevent the surface from vibrating smaller areas and a channel 31 is formed in the periphery for stiffening it. The channel 31 is preferably made rectangular in cross section in order to provide suitable seating surface for the book damping members 22 and 23 and its outer edge is preferably lower than its inner edge.

The central portion 32 of the diaphragm is slightly conical in form but only sufficient to compensate by thermal expansion for changes in volume of the electrode chamber, as described in U. S. Patent 1,570,120, granted to me on Jan. 19, 1926. It is also provided with radial corrugations to give it stiffness. As shown in the drawing, the transmitter button is mounted on the convex side of the diaphragm. Obviously, however, it may be mounted on the concave side of the diaphragm in any well known manner in which case the central portion should be dished in the opposite direction to the outer portion.

For convenience in handling the damping rings of each of the book damping elements 21, 22 and 23 are punched or stamped from the required number of sheets of material and at the same time are pierced with a sharp pointed tool such as a needle. The burrs of adjacent elements interlock as shown in Fig. 4 to hold them together and make it unnecessary to handle the individual rings. It is preferable in piercing the damping rings to pierce them near one edge so as to leave the remaining portion of the rings loose enough for air films to form between them. To accommodate the burrs, it is necessary to provide a depression either in the mounting or in the diaphragm. In the present case, the channel 31 in the periphery of the diaphragm provides depressions on each side thereof for the burrs in the damping rings 22 and 23. The central portion 32 being slightly depressed, provides a slight shoulder permitting the burrs on the damping means 21 to be turned toward the diaphragm. The burrs on the damping means 21, 22 and 23 engage the diaphragm and prevent the damping means from shifting.

What is claimed is:

1. An acoustic device comprising a diaphragm having a U shaped peripheral flange, damping means disposed against said flange for controlling the action of the diaphragm, said damping means comprising a plurality of thin washers having interlocking burrs, the burrs projecting into the recess provided by said flange.

2. In a telephone transmitter, a carbon containing chamber, a diaphragm, the central portion of which is in operative relation to the carbon in said chamber, damping means between the walls of said chamber and said diaphragm, and additional damping means disposed on each side of the periphery of said diaphragm and forming a mounting therefor, said damping means comprising a bundle of rings of thin sheet material secured together by a plurality of interlocking burrs on each adjacent ring.

3. In an acoustic device, a diaphragm comprising a centrally disposed conical-shape portion having radial corrugations and a radially corrugated conical outer portion of different slope, said outer portion having at its periphery a cylindrical flange, said flange forming one wall of a rectangular corrugation in said diaphragm and means supporting said diaphragm for substantially free movement.

4. In a telephone transmitter, the combination of a carbon chamber, a light, stiff diaphragm in the form of a truncated cone having a radially corrugated central portion forming a closure for said carbon chamber, said central portion being slightly dished or set in the direction of the carbon chamber, a main portion having a radially corrugated conical surface, a peripheral portion having a concentric corrugation of rectangular cross-section and book-damping means on each side of said peripheral portion and between the edge of said carbon chamber and the diaphragm.

In witness whereof, I hereunto subscribe my name this 14th day of August, A. D. 1925.

ARTHUR F. BENNETT.
